ERNEST E. BROOKS, OF FRAMINGHAM, MASSACHUSETTS, ASSIGNOR TO DENNISON MANUFACTURING COMPANY, OF FRAMINGHAM, MASSACHUSETTS, A CORPORATION OF MASSACHUSETTS

POWDER BOX

Application filed April 10, 1929. Serial No. 353,988.

This invention relates to containers formed of sheet material such as cardboard or heavy paper, and pertains more particularly to improvements in the method of making powder boxes, or the like, and to the resulting product.

In order economically to manufacture boxes adapted to contain finely divided material, such as powder, from such inexpensive material as cardboard, it is usually desirable to assemble the box from two or more preformed sections or units, comprising a bottom compartment, a powder-holding member or drum adapted to fit within the bottom compartment, and preferably a top member for covering the exposed end of the powder drum. In the completed article the powder compartment customarily has, cemented over its outer end, an outer head or covering of thin paper which confines the powder within the drum until the powder is to be used by the purchaser, who may readily cut or break away the paper to expose the powder; and in practicing the present invention this paper head is preferably applied to the powder drum before the box elements are assembled.

Considerable difficulty has heretofore been experienced in devising an economical and satisfactory method of so sealing the powder drum within the bottom compartment or shell of the box as to prevent the powder from sifting out of the bottom of the drum through the joints between the two members. This objectionable feature is especially difficult to overcome when, as in the present case, it is desirable to reduce manufacturing costs to the minimum by the elimination of special sealing sheets or other separate closures at the bottom of the drum.

It is accordingly the general purpose of the present invention to provide a simple and economical way of preparing and assembling the component units of the powder box so that the inner end of the drum is adhesively united to the bottom compartment in such a manner as effectively to prevent the filtration of loose powder through said joint. Important steps in the attainment of this purpose include first coating the contacting

surface of the bottom member with a normally non-tacky adhesive, prior to the assemblage of the box parts and preferably during the formation of the bottom compartment; subsequently, preferably immediately before the application of the powder drum thereto, softening the non-tacky coating by heat, or by heat and moisture, as by exposing the coated compartment to a blast of hot air or steam; and then pressing the exposed edges of the powder-filled drum against said coated surfaces while the adhesive is in a soft and sticky condition. It has been found that this method of adhesively uniting the abutting faces of the two parts not only is superior in effectiveness and especially in neatness to the ordinary modes of connecting box parts, but also affords substantial savings in the cost of production by dispensing with the time-consuming hand labor usually necessary in applying adhesives to the inner corners of the boxes.

Further objects of this invention will become apparent as the improved process and its resulting product are more fully explained in the following description, taken in connection with the accompanying drawings which show successive stages in the production of a powder box exemplifying a recommended embodiment of the invention. In said drawings:

Fig. 1 is a plan view of the bottom compartment or shell of the improved box;

Fig. 2 is a section to larger scale taken on line 2—2 of Fig. 1;

Fig. 3 is a perspective of the powder section or drum;

Fig. 4 is a sectional view of the assembled shell and drum in inverted position; and

Fig. 5 is a side view, partly in section, of the completed box equipped with a cover.

As suggested above, the component sections of the box are preferably constructed separately by the usual forming operations performed by hand or by suitable machinery. For example, the bottom compartment or shell (Figs. 1 and 2) may be shaped from a blank of cardboard to provide a bottom 6 and upwardly bent sides 7, and may be covered on the outside with an adhesively

100

applied layer of paper 8 which is preferably folded over the upper edges of the side walls, as at 9.

The inner surfaces of the bottom and side walls, at least at the margins of the bottom and preferably over the entire exposed areas of said portions, are coated with an adhesive 10, such as a suitable vegetable or animal glue, which is substantially non-tacky when cold and which when heated or moistened becomes sufficiently sticky to unite with other surfaces pressed into contact therewith. This adhesive may be applied to the blank before the compartment is folded into box-like form and, owing to its non-tacky condition at normal room temperatures, the coating does not interfere with proper manipulation of the material to form the compartment or shell.

For purposes which will later become apparent, grooves or recesses 11 are formed in the bottom 6 adjacent the sides 7 in the manner of a continuous trough surrounding said bottom. This marginal groove may conveniently be provided by affixing a cardboard sheet 12 upon the bottom 6, the size of the sheet or platform 12 preferably being such that the groove 11 closely receives the open end or edges of the powder drum. Obviously the raised platform 12 may be integral with the bottom 6, or the groove 11 may be formed by flanges or ribs upstanding from the bottom; and in case the powder drum has a marginal end wall surrounding a central opening, the width of the groove will be increased to accommodate said end wall.

The powder section or drum (Fig. 3) preferably comprises cardboard sides 13 suitably jointed at the corners of the rectangular structure, and having a paper covering 14 applied over one edge and extending part way along the inner and outer surfaces of the walls. The paper covered end of the drum is provided with an enclosing head preferably consisting of a thin, tearable strip of paper 15 which is adhesively affixed thereto; while the opposite end of the drum is uncovered or formed with a filling opening. As indicated above, the wall edges or margins at the open end of the drum are adapted to fit within the groove 11 of the bottom shell. This drum is substantially filled with powder through said open end before it is affixed to the shell.

Prior to the assembling of these two box elements and in order to render the cold adhesive coating sticky, the coating is preferably exposed to moist heated air, as by ejecting steam into the shell. The coating may, however, be softened by heating the cardboard shell or the adhesive itself by other suitable mediums. In such tacky condition, the shell is inverted and telescoped over the open end of the filled drum (Fig. 4), and the two parts

are pressed together so that the adhesive coating binds the end of the drum within the groove 11 and preferably unites the contacting side walls of the members. The drum is preferably of such depth that its paper covered end projects beyond the upper edge of the shell so that, after inverting the assembled box members, a paper covered top section 16 may be removably applied thereto, as shown in Fig. 5.

The manufacture of a powder box in the manner herein described involves simple operations upon inexpensive materials, yet the article thereby produced is rigid and durable in use, attractive and ornamental in appearance, and so constructed as effectively to prevent the objectionable sifting of powder through the joints between its assembled shell and drum components. The box may obviously be fashioned in any appropriate size or shape and exteriorly ornamented as desired. It will also be understood that details of the process of manufacture or the structure of the product may be varied to suit particular purposes without departing from the essence of this invention as defined in the following claims. For example, the box sections may be molded with continuous walls in cylindrical or other desired shape; and, in many satisfactory forms of the improved article, the marginal groove 11 may be omitted without sacrifice of operative efficiency.

I claim:

1. A method of making boxes for containing powder or the like, comprising forming a normally non-tacky, adhesive coating upon the interior bottom margins of a box shell, heating said coating to render it sticky, and pressing the open end of a powder containing drum into said shell and against the sticky coating.

2. A method of making boxes for containing powder or the like, comprising applying an adhesive which is non-tacky when cold and sticky when heated, to the box material so that the adhesive coats the meeting surfaces at the interior end of a formed box shell, softening the cold coating by heat to render it sticky, and pressing the open end of a powder containing drum into said shell and against the sticky coating.

3. A method of making boxes for containing powder or the like, comprising applying an adhesive coating which is non-tacky at normal room temperatures and sticky when exposed to heat and moisture, to the bottom and sides of a box shell adjacent the interior end of the shell, directing steam against the non-tacky coating to render it soft and sticky, and pressing the open end of a powder-filled drum into the shell and against the sticky coating.

4. A method of manufacturing boxes for containing powder or the like, comprising coating portions of a blank of sheet material

with an adhesive which is non-tacky at normal room temperature and which becomes sticky upon exposure to heat, forming the blank into an open-ended box shell while the 5 coating is non-tacky, so that the coating extends around the bottom margin and adjacent portions of the sides of the shell at the interior end thereof, directing a hot gaseous stream against the coating to render it sticky, 10 and then inserting the open end of a pre-formed, powder-filled drum into the shell and against the sticky coating.

15 Signed by me at Framingham, Massachusetts, this 6th day of April, 1929.

15 ERNEST E. BROOKS.
